[57] ABSTRACT

A hoist motor operates a hoist load shaft through an overload clutch having a circular gear that is in frictional relation to a disc member for applying a predetermined amount of torque for lifting a load, and slipping when there is overload. The disc member is mounted through screw threads on the load shaft and pressing the member against a shoulder to transmit the predetermined torque in load lifting direction. The screw threads have a limited length in axial direction that causes them in effect to disengage when the hoist motor rotates the disc in load lowering direction. The clutch cannot then apply the predetermined torque but a spring presses end portions of the threads against each other so as to transmit torque that is limited to a small amount, much less than the frictional surfaces of the clutch would accept. The load shaft operates a load chain having a limit member that strikes a stop surface on the hoist frame to limit lowering movement of the hoist. The hoist stress that is due to the small amount of lowering torque, when added to the considerable stress that may be due to a load when the chain limit member strikes the stop surface of the hoist, will be insufficient to overstress parts of the hoist.

STRESS LIMITING HOIST

FIELD OF INVENTION

The novel hoist of my invention is of the kind having a motor driven operating shaft that applies torque in opposed directions effecting rotation of a load shaft for lifting and lowering a load. My hoist particularly will limit the stresses that may be due to torque that the motor applies in either direction.

BACKGROUND OF INVENTION

As will be appreciated by those skilled in the art, hoists frequently are abused by attempts of an operator to utilize the hoist for lifting a load that weighs more than the safe capacity of the hoist, causing stresses that are injurious to the hoist and that are a source of danger to persons near the hoist. Therefore, designers working in the art have conceived various hoists that will limit the amount of load to be lifted, sometimes requiring electrical circuits and equipment for stopping operation of the hoist motor when the hoist is overloaded. One of the more satisfactory types of construction utilizes a torque limiting clutch that will yield when there is an attempt to lift a load that is excessive. In fact, the hoist designed by Suez and Smith and shown by their U.S. Pat. application Ser. No. 155,979 comprises a torque limiting clutch that acts to extremely good effect under conditions of overload. However, so far as I am aware, there does not exist in the prior art a hoist in which a torque limiting clutch will be fully effective to control stresses to which the hoist may be subjected when the hoist moves in a lowering direction.

In theory, a hoist motor need apply no power in order to lower a load. In practice, the motor in hoists of the particular kind does act to effect operation of the hoist in lowering direction, it being necessary to apply a small amount of power in order to overcome friction between parts of the hoist and to control the lowering movements of the load member of the hoist. If the hoist motor, when acting in lowering direction, can apply the amount of power that it applies in lifting direction, the power is excessive and tends to cause stresses that actually are unnecessary. Those stresses may reach a considerable magnitude when, as may happen, a part of the hoist meets an obstruction to its lowering movement. I now contribute by my invention a novel hoist that will place a low limit on the stresses that may be incidental to a lowering movement of the hoist, while also being effective to limit to a predetermined amount the stresses that the hoist need accept when operating in load lifting direction.

SUMMARY OF THE INVENTION

In the hoist of my invention, I connect a torque limiting clutch between an operating shaft and a load shaft of the hoist, said clutch comprising parts movable to a position that is effective to apply a predetermined amount of torque between the operating shaft and the load shaft, and to a further position that is ineffective to apply said predetermined amount of torque while the operating shaft rotates in that position.

The torque limiting clutch of my hoist may utilize parts that are frictionally related, one part being a circular gear meshing with one shaft, and having a tapered opening in spring pressed frictional relation to a tapered surface on a disc member that is mounted on another shaft. As a feature of my invention, the disc mem-

ber can move in axial direction so as to place the torque limiting clutch in positions that will accept differing amounts of torque relatively to its shaft.

- As a preferred feature, I mount the torque limiting clutch to rotate on screw threads whereby to move between a load lifting position and a load lowering position on a shaft, the screw threads being formed so as to substantially disengage whereby the clutch while in its load lifting position may rotate relatively to the shaft.
- 5 As a particular feature of this part of my invention, my hoist has spring means that press end portions of the screw threads against each other so as to apply a degree of torque between the clutch and its shaft while the clutch rotates in its load lowering position.
- 10 15 A further feature of my invention resides in stop means that will engage positively to limit lifting and lowering movements of a hoist load member, in combination with stress limiting means that will effectively limit the stresses that are incidental to the limiting effect of the stop means in either direction. More particularly, the stress limiting means will limit to a relatively small amount the stresses that are due to engagement of the stop means while the hoist motor acts in lowering direction.
- 20 25 I have thus outlined rather broadly the more important features of my invention in order that the detailed description thereof that follows may be better understood, and in order that my contribution to the art may be better appreciated. There are, of course, additional features of my invention that will be described hereinafter and which will form the subject of the claims appended hereto. Those skilled in the art will appreciate that the conception on which my disclosure is based may readily be utilized as a basis for the designing of other structures for carrying out the several purposes of my invention. It is important, therefore, that the claims be regarded as including such equivalent constructions as do not depart from the spirit and scope of my invention, in order to prevent the appropriation of my invention by those skilled in the art.

DESCRIPTION

In the drawings:

FIG. 1 shows a plan view, partly in section, of a hoist that utilizes my invention.

FIG. 2 shows an end view, partly in section on the line 2-2 in FIG. 1.

Referring now more particularly to FIG. 1 of the drawings, I show my hoist 10 equipped with a rather usual hoist motor 11 and motor brake 12 that are mounted on opposed ends of a hoist frame 13. Connecting the motor 11 and brake 12 is a drive shaft 14 extending through a hollow load shaft 15. A gear portion 16 on shaft 14 meshes with a gear 17 that is keyed to an operating shaft 18 so that motor 11 will rotate that shaft, each of the shafts being mounted through suitable bearings to rotate on hoist frame 13. I believe it will be unnecessary to describe in detail the functional relation between motor 11 and brake 12 because that relation is quite conventional, and I shall merely indicate that brake 12 is so controlled automatically as to permit drive shaft 14 to rotate when motor 11 is energized, and oppose rotation when the motor is not energized.

In the novel concept of my invention, the operating shaft 18 and load shaft 15 are connected through a torque limiting clutch, indicated generally by the nu-

meral 20 in FIG. 1. Clutch 20 includes a circular gear 21 meshing with a pinion 22 that is formed on the operating shaft 18, and an inner disc member 23 that is mounted through screw threads 24, 25 coaxing on member 23 and load shaft 15. The peripheral surface of disc member 23 and the opening of circular gear 21 have a shape that is tapered, and friction material 26 is interposed so as to offer frictional surfaces engaging between gear 21 and member 23. One or more spring discs 27 are held by a retaining ring 28 on a hub portion of disc member 23 and press against circular gear 21 so as to hold the gear and member in frictional engagement. The disc member 23 then will accept a predetermined amount of torque that may be applied through rotation of the operating shaft 18, while an excessive amount of torque will be absorbed by frictional slip-page.

As shown in FIG. 1, the load shaft 15 has a shoulder 29 forming stop means for the disc member 23. Also, the screw threads 24, 25 are so inclined that the disc member 23 when rotating in load lifting direction will press against shoulder 29, forming a positive connection so that the torque limiting clutch 20 then is in position to apply its predetermined amount of torque to load shaft 15. When rotating in direction to lower a load, disc member 23 naturally will move on screw threads 24, 25 away from shoulder 29, or toward the right as viewed in FIG. 1.

I call attention to the fact that screw threads 24, 25 have a relatively limited length in axial direction, such that they will substantially disengage to terminate their screw action when disc member 23 continues to rotate in load lowering direction. The torque limiting clutch 20 then is in a further position that may be termed a load lowering position, in which disc 23 rotates while end portions 33, 34 of the screw threads 24, 25 remain in contact with each other. I particularly hold the thread end portions 33, 34 in contacting relation, utilizing for the purpose a spring plate 30 mounted on the hoist frame, as by screws 31. That plate 30 has a series of spring fingers 32 pressing against the torque limiting clutch 20 or its spring discs 27 while the clutch is in its load lowering position. The pressure applied by spring fingers 32 will be accepted between the end portions 33, 34 of the screw threads, causing the disc member 23 to apply a small amount of torque in load lowering direction to the load shaft 15. The torque that can be so applied will be limited and much less than the predetermined amount that can be applied through the frictional relation between disc member 23 and gear 21. It may be mentioned here that the spring pressure applied by spring fingers 32 also will cause screw threads 24, 25 to engage fully so that the clutch 20 will move to its load lifting position against the shoulder 29 when disc member 23 rotates in load lifting direction.

It will thus be seen that the torque limiting clutch 20 will move to a load lowering position in which the hoist motor can cause no more than a small amount of stress in the hoist, and also to a load lifting position in which the motor may cause a limited but larger amount of stress that is necessary for lifting a predetermined load.

I shall now refer to FIG. 2 to describe the manner in which the torque limiting features of my invention will act in relation to a hoist load member. For the purpose of description, I show a load chain 36 forming the load member and engaging a chain sheave 35 formed on the load shaft 15 (FIG. 1), as is quite usual in the art. Chain

36 is equipped with a load hook 37 for engaging a load while the hoist is supported through a hook 38 on the hoist frame 13, and the chain has a slack portion 39 secured at 40 to frame 13. To limit the lifting and lowering movements of load chain 36, as is necessary, I show an extremely simple arrangement in which lifting limit and lowering limit members 41, 42 are secured to appropriate points on chain 36 and its slack portion 39 for engaging a stop portion on frame 13. Due to the action of torque limiting clutch 20, as I have described, it will be understood that a movement of lifting limit member 41 against stop portion 43 will cause no more than a predetermined amount of stresses in the hoist and its chain 36.

To understand stresses that are incidental to lowering operation of the hoist motor, let us assume first that the hook 37 supports a load. While the chain 36 moves in lowering direction, its stresses will be substantially those that are due to the load. Now consider that the chain 36 reaches its lower limit position, in which the slack chain portion 39 is in its dotted line position 39a and limit member 42 is in its position 42a against the frame stop portion 43. In the position 42a of limit member 42, the limit member will accept the load, thus causing the stress that is due to the load to be applied to that part 44 of the chain that extends between chain sheave 35 and member 42. That stress may be of a large magnitude, and it then is important that no great amount of stress be added to the chain part 44.

It will be remembered that my torque limiting clutch 20 will apply very little torque in load lowering direction to the load shaft 15. Therefore, should the hoist motor continue to operate while chain 36 is in its lower limit position, chain sheave 35 will add merely a small amount of stress to that which the load causes in the part 44 of the chain. Thus, it is possible through the concept of my invention to utilize extremely simple and positive stop means to limit lowering movements as well as the lifting movements of a hoist load member, while effectively limiting the stresses that may be due to the operation of the stop means.

I believe that the construction and the operation of my novel stress limiting hoist now will be understood, and that persons who are skilled in the art will fully appreciate that I have made a contribution of very considerable value to the hoist industry.

I claim:

1. In a hoist having a load shaft, a load member connected to the load shaft, and a motor driven operating shaft rotatable in opposed directions effecting rotation of the load shaft whereby to lift and to lower a load supported on the load member, a torque limiting clutch connected between said shafts, said torque limiting clutch being longitudinally movable between said shafts to a first position that is effective to engage said clutch with one of said shafts to apply a predetermined amount of torque between the operating shaft and the load shaft, and to a second position that is effective to disengage said clutch to make said clutch ineffective to apply said predetermined amount of torque to said load shaft while allowing the operating shaft to rotate, and means for longitudinally moving said clutch to said first and second position in response to load lifting and load lowering rotation of said operating shaft so as to place differing limits on the hoist stresses that the operating shaft may cause through the load shaft.

2. The combination set forth in claim 1 in which there are means acting in response to the operating shaft torque to move said clutch mentioned to said first-mentioned position when the torque is in load lifting direction and to said further position when the torque is in load lowering direction.

3. The combination set forth in claim 2, including a lifting limit member secured in position on said load member to engage a stop portion on the hoist so as to limit positively the extent of lifting movement of the hoist, said torque limiting clutch being effective to limit to a small amount the hoist stresses that are due to the applied torque when said limit member engages said stop portion.

4. In a hoist having a load shaft, a load member connected to the load shaft, and a motor driven operating shaft rotatable in opposed directions effecting rotation of the load shaft whereby to lift and to lower a load supported on the load member, a torque limiting clutch connected between said shafts, said torque limiting clutch comprising parts movable to a position that is effective to apply a predetermined amount of torque between the operating shaft and the load shaft, and to a second position that is ineffective to apply said predetermined amount of torque to said load shaft while the operating shaft rotates, means for moving said clutch parts to said first and second positions so as to place differing limits on the hoist stresses that the operating shaft may cause through the load shaft, means acting in response to the operating shaft torque to move said clutch parts to said first position when the torque is in load lifting direction and to said second position when the torque is in load lowering direction, said torque limiting clutch having parts that are frictionally related through surfaces engaging to accept said predetermined amount of torque, one of said parts being mounted for rotation relatively to one of said operating and load shafts, and there being means locking said one of the parts so as to rotate with said one of the shafts when the parts of the clutch move to their first position.

5. The combination set forth in claim 4 in which the means that move the clutch parts have portions that are in a rotatable relation enabling the clutch parts to remain in their further position while said one of the parts rotates relatively to said one shaft.

6. The combination set forth in claim 4 in which the means that move the parts of said torque limiting clutch comprises screw threads engaging between said one clutch part and one shaft, stop means against which the threads move said one part on said one shaft when moving the clutch parts to their first-mentioned posi-

tion, and end portions of said screw threads in opposed relation to each other when the clutch parts are in their further position and enabling the parts to remain in that position while said one part rotates in lowering direction relatively to said one shaft.

7. The combination set forth in claim 6 including a lifting limit member secured in position on said load member to engage a stop portion on the hoist so as to limit positively the extent of lifting movement of the hoist, said torque limiting clutch being effective to limit to a small amount the hoist stresses that are due to the applied torque when said limit member engages said stop portion.

8. In a hoist having a load shaft, a load member connected to the load shaft, and a motor driven operating shaft rotatable in opposed directions effecting rotation of the load shaft whereby to lift and to lower a load supported on the load member, a clutch longitudinally movable between said shafts to a first and a second position in response to load lifting and load lowering rotation of said operating shaft, means for moving said clutch to said first position to apply a predetermined amount of operating shaft torque in load lifting direction to the load shaft, said clutch yielding in said first position when the torque is greater than said predetermined torque, and means for moving said clutch to said second position to apply a relatively small amount of the operating shaft torque in load lowering direction to the load shaft, said clutch yielding in said second position when the amount of torque is less than said predetermined amount.

9. A combination set forth in claim 8 including lifting and lowering limit members secured in positions on said load member to engage a stop portion on the hoist so as to limit positively the extent of lifting and lowering movements of the hoist, while the means that apply torque in lifting and lowering directions yield.

10. The combination set forth in claim 9 in which the load member is a flexible member such as a chain engaging a wheel on the load shaft, said flexible member having at opposed sides of the wheel a load portion and a slack portion to which said lifting and lowering limit members are secured, the slack portion of the flexible member being stressed by a load on said load portion of the member when the lowering limit member engages the stop portion of the hoist, and said means that apply torque in load lowering direction limiting to a relatively small amount the stresses that an operation of the motor driven shaft can add to said stressing of the slack portion of the flexible member.
